(57) **CLAIM**

The ornamental design for a microphone, as shown and described.

DESCRIPTION

FIG. 1 is a front elevational view of a microphone showing my new design;

FIG. 2 is a top plan view thereof;

FIG. 3 is a side elevational view of one side thereof; and, FIG. 4 is a side elevational view of the opposite side thereof. The broken line showings of the central circle on the front, the trapezoid shaped area on the left side and the frustoconical element on the bottom are for illustrative purposes only and form no part of the claimed invention.
